UNITED STATES PATENT OFFICE.

JOHN M. CURLESS, OF CEDAR RAPIDS, IOWA.

IMPROVEMENT IN CHIMNEY-SWEEPING APPARATUS.

Specification forming part of Letters Patent No. **148,184**, dated March 3, 1874; application filed July 21, 1873.

To all whom it may concern:

Be it known that I, JOHN M. CURLESS, of Cedar Rapids, in the county of Linn and State of Iowa, have invented a new and useful Improvement in Chimney-Sweeping Apparatus, of which the following is a full, clear, and exact description, reference being had to the annexed drawing, in which—

The drawing, Figure 1, illustrates a perspective view of my improved chimney-sweeping apparatus, and Fig. 2 an end view thereof.

The nature of this invention consists of a receptacle or box, having its back elongated or extended in an upward direction, which elongation or extension is supplied with parallel plates or a socket to receive a brush or brushes secured therein in any known way, and an aperture or other means to permit of the attachment of suitable means for manipulating the apparatus.

To enable others to make and use my invention, I will proceed to describe it.

In the drawing hereto annexed, A refers to a receptacle for receiving the soot as it is brushed from the chimney, and which has its back extended upward a suitable distance, as shown at *a*, to enable the brush or brushes to be disposed above the entrance of the receptacle or box. An opening or aperture is punched or otherwise made in the extension *a* of the back of the receptacle to permit of the attachment thereto of a rod or other suitable means for lifting and lowering the same in the chim-

ney. B B refer to a series of brushes, or, in lieu thereof, a single brush may be substituted, which are held in any known way between the plates or lips *b b*, soldered or otherwise fastened at their right-angular portions to the extension *a* of the receptacle, so as to allow the said brushes or brush to overhang the entrance of the latter.

By this arrangement the soot taken by the brushes from the chimney will be caught by the receptacle.

I am aware that receptacles have been adapted to brushes in various ways to catch dirt, &c., as, for example, in sweeping-machines, and I therefore do not lay claim, broadly, to the combination of these parts; but

Having thus described my invention, what I claim, and desire to secure by Letters Patent, is—

As a new article of manufacture, the chimney-sweeping apparatus herein shown and described, consisting of the receptacle A *a*, and the brushes B B, arranged to project horizontally over the top of the receptacle, substantially as and for the purpose set forth.

In testimony whereof I have hereunto signed my name this 28th day of June, 1873, in presence of two subscribing witnesses.

JOHN M. CURLESS.
